Primary Examiner — Freda S Nunn

(57) **CLAIM**

The ornamental design for a ceiling mounted dual display touchscreen computer monitor, as shown and described.

DESCRIPTION

FIG. 1 is a bottom, front and right side perspective view of the ceiling mounted dual display touchscreen computer monitor showing my new design without the spiral, power and data cables attached;

FIG. 2 is a bottom, rear and left side perspective view thereof;

FIG. 3 is a bottom plan view thereof;

FIG. 4 is a front elevational view thereof;

FIG. 5 is a left side view thereof;

FIG. 6 is a right side view thereof;

FIG. 7 is a rear elevational view thereof;

FIG. 8 is a top plan view thereof;

FIG. 9 is a rear view thereof with the spiral, power and data cables attached;

FIG. 10 is a left side view thereof;

FIG. 11 is a right side view thereof;

FIG. 12 is a rear elevational view thereof;

FIG. 13 is a top, rear and left side perspective view thereof;

FIG. 14 is a top, front and left side perspective view thereof; and,

FIG. 15 is a top, front and right side perspective view thereof.
